HAT STAND

Frank S. Sander, Stamford, Conn., assignor to
My Double Company, Inc., Stamford, Conn.
Filed May 13, 1963, Ser. No. 279,880
8 Claims. (Cl. 211—33)

The present invention relates to a hat stand or form. More particularly, the invention relates to a hat stand which may be adjusted so as to correspond to the configuration of any specific hat. The hat stand of the present invention may also be used as a wig stand in which case it is particularly desirable to have the configuration of the hat form conform to the head of the person intending to wear the wig.

The hat form of the present invention is made of a material which is sufficiently rigid so that the hat form will retain whatever shape it has been bent to, however, the material is also sufficiently flexible so that it may be bent into the desired shape, and, at some other times may be reshaped to correspond to the configuration of a different head.

It is an object of the present invention to provide a hat form which may be adjusted to the shape or configuration of a variety of heads.

It is another object of the present invention to provide a hat form of improved construction so as to obtain the necessary stiffness and rigidity of the structure together with easy adjustability.

It is a further object of the present invention to provide a hat form and a hat stand which can be easily and economically produced.

Other objects and advantages of the present invention will become apparent from a further reading of the description and of the appended claims.

With the above and other objects in view, the present invention contemplates a hat and wig stand, comprising, in combination, an adjustable hat form including a dome-shaped top portion and a lateral portion extending downwardly from at least the major part of the periphery of the dome-shaped top portion, the adjustable hat form consisting essentially of a network of flexible substantially non-resilient relatively soft and deformable thin rods at least the surface portion of which consists of plastic material, and of elongated sleeve-shaped connecting members rigidly enclosing the rods at the connecting points of the network in such a manner that the rod portions within the sleeve-shaped connecting members are deformed, thus preventing turning and other relative movement of the connected thin rods at the connecting points relative to each other, and support means having a base and an upper portion located higher than the base and engaging the hat form so that the hat form is upwardly spaced from the base.

According to a preferred embodiment of the present invention, the same consists in an adjustable hat form including a dome-shaped top portion having an apex and a peripheral portion located in a plane downwardly of the apex and also including a lateral portion extending downwardly from at least the major part of the peripheral portion of the dome-shaped top portion and terminating in a lower edge portion, the hat form having an axis extending downwardly from the apex of the dome-shaped top portion substantially perpendicular to the plane in which the peripheral portion is located, the adjustable hat form comprising, in combination, a network of flexible substantially non-resilient relatively soft and deformable thin rods at least the surface portion of which consists of plastic material; elongated sleeve-shaped first connecting members rigidly enclosing the rods at first connecting points of the network in such a manner that the

2

rod portions with the sleeve-shaped first connecting members are deformed thus preventing turning and other relative movement of the connected thin rods at the first connecting points relative to each other, the first sleeve-shaped connecting members, respectively, extending substantially in the direction from the lower edge of the lateral portion towards the apex of the dome portion; at least two second sleeve-shaped connecting members located in the dome-shaped top portion spaced from the apex and the peripheral portion thereof and substantially located in a plane extending perpendicular to the axis, the second sleeve-shaped connecting members rigidly enclosing a minor portion of the rods at second connecting points of the network in such a manner that the rod portions within the sleeve-shaped second connecting members are deformed thus preventing turning and other relative movement of the connected thin rods at the second connecting points relative to each other, and a plurality of the rods enclosed in the first connecting members at the first connecting points being of sinuous shape and located in the dome-shaped top portion in a plane parallel to and below the plane in which said second sleeve-shaped connecting members are located, the second connecting members and the rods of sinuous shape reducing the flexibility and adjustability of the dome-shaped top portion without affecting the flexibility and adjustability of the lateral portion, and means adapted to maintain the network of the lateral portion in adjusted state after it has been shaped in the required manner by bending the flexible rods of the lateral portion of the adjustable hat form, the means including two rigid elongated members of adjustable length adapted to be fixed at their ends to contacting portions of the rods and located in a first plane substantially perpendicular to the axis, and two rigid elongated members of adjustable length adapted to be fixed at their ends to contacting portions of the rods and located in a second plane extending substantially perpendicular to the axis and upwardly spaced from the first plane.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a plan view of a hat stand according to the present invention;

FIG. 2 is an elevational view of the hat stand shown in FIG. 1;

FIG. 3 is an elevational view of a modification of the hat stand of FIG. 2 taken at an angle of 90° thereto; and

FIG. 4 is a fragmentary elevational view of another embodiment of the hat stand according to the present invention.

Referring now to the drawings, it will be seen that the hat stand comprises a hat form and a support therefor. The support as illustrated in FIGS. 1-3, comprises a base 5, a stem portion 10 and an upper portion 6 which engages the hat form which will be described further below. According to FIGS. 1-3 upper portion 6 is rounded and engages the uppermost portion of the hat form; while according to FIG. 4 the upper portion 6' of the support means contacts a portion of the reinforcing structure 55 which is downwardly spaced from the top portion of the hat form.

The hat form comprises a dome-shaped upper or top portion 1 and a lateral portion 2 which extends downwardly from at least the major part of the periphery of dome-shaped top portion 1. The integral top and lateral portions consist essentially of a network of flexible, substantially non-resilient, relatively soft and deformable

thin rods 3 which may be thin wires, covered with a layer of plastic material, or which also may consist in their entirety of suitable plastic material and of elongated sleeve-shaped connecting members 4 which rigidly enclose rods 3 at connecting points of the network formed thereof.

Connecting members 4 enclose adjacent rods at the connecting points of the network in such a manner that the rod portions within the sleeve-shaped connecting members will be deformed and thereby prevented from turning and other relative movements of the connected rods 3 at the connecting points 4 relative to each other.

Rods 3 are of such type as to be bendable into the required shape with relative ease and to retain their shape after they are bent. The plastic covered metal rods or just plain plastic rods are enclosed and gripped by the sleeve-shaped connecting members 4 at the intersecting points of the mesh structure formed thereof, whereby the rod portions within the connecting members will be deformed by the latter and thereby movement of the connecting rod portions relative to each other is prevented. It is preferable to provide on the connecting members projections which are bent inward into the plastic material of the rods of which the network consists. Such arrangement and the deformation of the rods caused thereby definitely prevents relative turning of the connected plastic rods.

The rods or plastic rods as described herein are intended to include not only rods consisting exclusively of plastic material but also such plastic rods which are hollow, i.e., tube-shaped or which contain a core of metal or other material. However, it is essential that at least the outer portion of the rods consist of plastic or other material that may be easily deformed by contact with the inwardly directed projections of connecting members 4.

In addition to connecting members 4 as described above and substantially extending in a direction towards the apex of the hat form, there are also provided in the dome-shaped portion 1 of the hat form a limited number, at least two, connecting members 7 which are located within the dome-shaped portion 1 spaced from the apex of the hat form, within a plane which is substantially perpendicular to the axis of the hat form, which axis substantially coincides with stem 10 of the support. Connecting members 7 together with the rods embraced by the same impart greater rigidity to dome-shaped portion 1, and in the nature of a reinforcing structure will make it somewhat more difficult to deform the part of the dome-shaped portion of the hat form which is located upwardly of connecting members 7.

In addition, at least two rods 8 which are located in the dome-shaped portion of the hat form below the plane of connecting members 7 are of sinuous or undulating shape. Sinuous rods 8 serve to further reinforce the dome-shaped portion of the hat form so as to give to the same a somewhat greater rigidity than that of the lateral portion 2. Preferably, sinuous rods 8 are connected at least at one end thereof, respectively, with a rod, which is also embraced by one of connecting members 7.

Once the hat form has been bent to the desired shape it is desirable to support the hat form in such shape in order to prevent unintentional further bending or deformation of the same. For this purpose, adjustable rods 9 are provided which preferably consist of an inner rod-shaped member 9' and an outer tube 9" surrounding the inner member 9' so that the total length of rod 9 may be adjusted by the degree to which the inner rod member 9' is inserted into the outer tube 9". Reinforcing member 9 terminates at its opposite ends in hook-shaped portions 11 which are adapted to grip rods 4.

Means are provided for locking inner rod 9' and outer tube 9" of reinforcing member 9 so as to maintain the desired distance between the hook portions 11 at the opposite ends of reinforcing member 9. The hook portions 11 are hooked into the meshes of the network formed by

rods 3 and thereby will fix the distance between the rod portions thus gripped by the opposite hook portions 11 of reinforcing member 9.

Preferably two pairs of elongated reinforcing members 9 are provided, arranged in two parallel planes, which are perpendicular to the axis of the hat form or to stem 10 of the support. Preferably the two elongated reinforcing members within one of these parallel planes are arranged parallel to each other and perpendicular to those located in the other of these two parallel planes.

It will be seen in FIG. 4, that the upper portion 6 of the support may contact, for instance, the two elongated reinforcing members 9 which are located in the lower of the two parallel planes, in which case, upper portion 6 must be of sufficiently large dimensions to span the distance between the two parallel rods 9 located in the lower plane.

On the other hand, when upper portion 6 of the support is to contact the uppermost portion of the hat form, then upper portion 6 must be sufficiently small to pass between the parallel reinforcing rods 9.

FIG. 1 shows four reinforcing rods 9 which are arranged in two planes with the two rods of each plane parallel to each other, FIG. 2 shows a rod located in the lower one of the two parallel planes, while FIG. 3 shows a rod 9' which is located in the upper of the two parallel planes.

Hook portions 11 are preferably arranged turnably at the ends of the rod and tube of reinforcing member 9 in order to enable their easy attachment to the wire network.

While rods 3 have been described to consist of plastic or of plastic covered wire, for instance of rubber or rubber covered wire, it is also within the scope of the present invention to form rods 3 of wires which are covered with a textile material or other suitable material into which the inwardly extending projections of connecting members 4 may penetrate so as to prevent movement of the rod portions within each connecting member 4 relative to each other.

It will be understood that each of the elements described above, or two or more together, may also find a useful application in other types of hat stands differing from the types described above.

While the invention has been illustrated and described as embodied in deformable hat and wig form, it is not intended to be limited to the details shown, since various modifications and structural changes may be made without departing in any way from the spirit of the present invention.

Without further analysis, the foregoing will so fully reveal the gist of the present invention, that others can, by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A hat and wig stand, comprising, in combination, an adjustable hat form including a dome-shaped top portion and a lateral portion extending downwardly from at least the major part of the periphery of said dome-shaped top portion, said adjustable hat form consisting essentially of a network of flexible substantially non-resilient relatively soft and deformable thin rods at least the surface portion of which consists of plastic material, and of elongated sleeve-shaped connecting members rigidly enclosing said rods at the connecting points of said network in such a manner that the rod portions within said sleeve-shaped connecting members are deformed, thus preventing turning and other relative movement of said connected thin rods at said connecting points relative to each other; and

support means having a base and an upper portion located higher than said base and engaging said hat form so that said hat form is upwardly spaced from said base.

2. A hat and wig stand, comprising, in combination, an adjustable hat form including a dome-shaped top portion and a lateral portion extending downwardly from at least the major part of the periphery of said dome-shaped top portion, said adjustable hat form consisting essentially of a network of flexible substantially non-resilient relatively soft and deformable thin rods at least the surface portion of which consists of plastic material, and of elongated sleeve-shaped connecting members rigidly enclosing said rods at the connecting points of said network in such a manner that the rod portions within said sleeve-shaped connecting members are deformed, thus preventing turning and other relative movement of said connected thin rods at said connecting points relative to each other; and support means having a base and an upper portion located higher than said base and engaging the underside of said dome-shaped top portion of said hat form so that said hat form is upwardly spaced from said base.

3. An adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-shaped first connecting members are deformed thus preventing turning and other relative movement of said connected thin rods at said first connecting points relative to each other, said first sleeve-shaped connecting members, respectively, extending substantially in the direction from the lower edge of said lateral portion towards the apex of said dome portion; and second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said sleeve-shaped second connecting members are deformed thus preventing turning and other relative movement of said connected thin rods at said second connecting points relative to each other, and a plurality of said rods enclosed in said first connecting members at said first connecting points being located in said dome-shaped top portion in a plane parallel to and below said plane in which said second sleeve-shaped connecting members are located.

4. An adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-

shaped first connecting members are deformed thus preventing turning and other relative movement of said connected thin rods at said first connecting points relative to each other, said first sleeve-shaped connecting members, respectively, extending substantially in the direction from the lower edge of said lateral portion towards the apex of said dome portion; and at least two second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said second sleeve-shaped connecting members are deformed thus preventing turning and other relative movement of said connected thin rods at said second connecting points relative to each other, and a plurality of said rods enclosed in said first connecting members at said first connecting points being of sinuous shape and located in a plane parallel to and below said plane in which said second sleeve-shaped connecting members are located.

5. An adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-shaped first connecting members are deformed thus preventing turning and other relative movement of said connected thin rods at said first connecting points relative to each other, said first sleeve-shaped connecting members, respectively, extending substantially in the direction from the lower edge of said lateral portion towards the apex of said dome portion; at least two second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said sleeve-shaped second connecting members are deformed thus preventing turning and other relative movement of said connected thin rods at said second connecting points relative to each other, and a plurality of said rods enclosed in said first connecting members at said first connecting points being of sinuous shape and located in said dome-shaped top portion in a plane parallel to and below said plane in which said second sleeve-shaped connecting members are located, said second connecting members and said rods of sinuous shape reducing the flexibility and adjustability of said dome-shaped top portion without affecting the flexibility and adjustability of said lateral portion; and means adapted to maintain the network of said lateral portion in adjusted state after it has been shaped in the required manner by bending the flexible rods of the lateral portion of said adjustable hat form.

6. An adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower

edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-shaped first connecting members are deformed thus preventing turning and other relative movement of said connected thin rods at said first connecting points relative to each other, said first sleeve-shaped connecting members, respectively, extending substantially in the direction from the lower edge of said lateral portions towards the apex of said dome portion; at least two second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said sleeve-shaped second connecting members are deformed thus preventing turning and other relative movement of said connected thin rods at said second connecting points relative to each other, and a plurality of said rods enclosed in said first connecting members at said first connecting points being of sinuous shape and located in said dome-shaped top portion in a plane parallel to and below said plane in which said second sleeve-shaped connecting members are located, said second connecting members and said rods of sinuous shape reducing the flexibility and adjustability of said dome-shaped top portion without affecting the flexibility and adjustability of said lateral portion; and means adapted to maintain the network of said lateral portion in adjusted state after it has been shaped in the required manner by bending the flexible rods of the lateral portion of said adjustable hat form, said means including two rigid elongated members of adjustable length adapted to be fixed at their ends to contacting portions of said rods and located in a first plane substantially perpendicular to said axis, and two rigid elongated members of adjustable length adapted to be fixed at their ends to contacting portions of said rods and located in a second plane extending substantially perpendicular to said axis and upwardly spaced from said first plane, said rigid elongated members of said first plurality extending in a direction substantially perpendicular to the direction of said rigid elongated members of said second plurality.

7. An adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-shaped first connecting members are deformed thus preventing turning and other relative movement of said connected thin rods at said first connecting points relative to each other, said first sleeve-shaped connecting members, respectively, extending substantially in the direction from the lower edge

of said lateral portion towards the apex of said dome portion; at least two second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said sleeve-shaped second connecting members are deformed thus preventing turning and other relative movement of said connected thin rods at said second connecting points relative to each other, and a plurality of said rods enclosed in said first connecting members being of sinuous shape and located in said dome-shaped top portion in a plane parallel to and below said plane in which said second sleeve-shaped connecting members are located, said second connecting members and said rods of sinuous shape reducing the flexibility and adjustability of said dome-shaped top portion without affecting the flexibility and adjustability of said lateral portion; and means adapted to maintain the network of said lateral portion in adjusted state after it has been shaped in the required manner by bending the flexible rods of the lateral portion of said adjustable hat form, said means including two rigid elongated members of adjustable length adapted to be fixed at their ends to contacting portions of said rods and located in a first plane substantially perpendicular to said axis, and two rigid elongated members of adjustable length adapted to be fixed at their ends to contacting portions of said rods and located in a second plane extending substantially perpendicular to said axis and upwardly spaced from said first plane.

8. A hat and wig stand comprising, in combination, and adjustable hat form including a dome-shaped top portion having an apex and a peripheral portion located in a plane downwardly of said apex and also including a lateral portion extending downwardly from at least the major part of the peripheral portion of said dome-shaped top portion and terminating in a lower edge portion, said hat form having an axis extending downwardly from the apex of said dome-shaped top portion substantially perpendicular to the plane in which said peripheral portion is located, said adjustable hat form comprising, in combination, a network of flexible substantially non-resilient relatively soft and deformable thin rods at least the surface portion of which consists of plastic material; elongated sleeve-shaped first connecting members rigidly enclosing said rods at first connecting points of said network in such a manner that the rod portions within said sleeve-shaped first connecting members are deformed thus preventing turning and other relative movement of said connected thin rods at said first connecting points relative to each other, said first sleeve-shaped connecting members, respectively, extending substantially in the direction from the lower edge of said lateral portion towards the apex of said dome portion; at least two second sleeve-shaped connecting members located in said dome-shaped top portion spaced from the apex and the peripheral portion thereof and substantially located in a plane extending perpendicular to said axis, said second sleeve-shaped connecting members rigidly enclosing a minor portion of said rods at second connecting points of said network in such a manner that the rod portions within said sleeve-shaped second connecting members are deformed thus preventing turning and other relative movement of said connected thin rods at said second connecting points relative to each other, and a plurality of said rods enclosed in said first connecting members at said first connecting points being of sinuous shape and located in said dome-shaped top portion in a plane parallel to and below said plane in which said second sleeve-shaped connecting members are located, said second connecting members and said rods of sinuous shape

reducing the flexibility and adjustability of said dome-shaped top portion without affecting the flexibility and adjustability of said lateral portion; means adapted to maintain the network of said lateral portion in adjusted state after it has been shaped in the required manner by bending the flexible rods of the lateral portion of said adjustable hat form, said means including a first plurality of rigid elongated members of adjustable length adapted to be fixed at their ends to contacting portions of said rods and located in a first plane substantially perpendicular to said axis, and a second plurality of rigid elongated members of adjustable length adapted to be fixed at their ends of contacting portions of said rods and located in a second plane extending substantially

perpendicular to said axis and upwardly spaced from said first plane, said rigid elongated members of said first plurality extending in a direction substantially perpendicular to the direction of said rigid elongated members of said second plurality; and support means having a base and an upper portion located higher than said base and engaging said hat form so that the same is upwardly spaced from said base.
